Inventor:
Walter G.E. Smith.

64 I. G. Haasler, Atto.

UNITED STATES PATENT OFFICE

WALTER G. E. SMITH, OF PORTLAND, OREGON

PULP STRAINER

Application filed March 19, 1928. Serial No. 262,859.

My invention relates to pulp strainers, employed in the art of paper making.

The object of my invention is to provide a simple and efficient pulp strainer—also commonly known in the art as screen plate vat—of the type in which the screen plates are removable, to facilitate cleaning and repairing and in which the means provided for clamping the screen plates in the bottom of the vat are quickly and conveniently releasable.

Another object of my invention is to provide clamping devices adapted to be in part housed in the side walls of the vat, and each comprising a clamping screw bearing on the ends of transverse beams provided for holding the screen plates in proper spaced relation, and a supplementary clamping screw adapted to bear on longitudinal lining-and-clamping bars bearing on the ends of the screen plates to hold them in place.

Another object of my invention is to provide clamping means adapted when released to lift the said lining-and-clamping bars clear of the screen plates, to facilitate cleaning.

A further object of my invention is to provide simple, inexpensive and efficient clamping means in the form of camping units each complete in itself and arranged in recesses provided therefor in the interior faces of the side walls of the vat, whereby the removable parts of the strainer are secured in place.

Thus my invention may be said in one phase thereof to comprise the combination of a pulp strainer comprising in combination a vat having its interior faces provided with vertical recesses, screen plates and removable transverse beams, for locking the screen plates in place, lining and clamping bars arranged along the interior faces of the vat walls bearing on the said screen plates, and provided with packing on their bearing faces, and means for securing the said beams and the said bars in place, such means adapted to permit the moving of the said bars from the screen plates without disturbing other parts of the strainer.

The above mentioned and other features of my invention are hereinafter fully described

with reference to the accompanying drawings, in which:

Fig. 1 shows a transverse section of my pulp strainer in its entirety;

Fig. 2 shows a perspective section illustrating the arrangement and operation of the means for securing the removable elements of my strainer in place in the vat thereof;

Fig. 3 shows in perspective one of the castings constituting a part of the means for clamping the removable elements in place in my strainer;

Figs. 4 to 7 inclusive illustrate details of construction more fully described in the body of this specification;

Fig. 8 shows on a smaller scale a plan of my pulp strainer in its entirety;

Fig. 9 is a larger scaled sectional elevation of the interior face of one wall of the vat of my strainer, illustrating the arrangement of the cooperating parts of my strainer and

Fig. 10 illustrates a wrench which may be conveniently employed for operating the clamping screws.

With reference to the figures, my invention comprises a rectangular vat *a* provided on its sides at the bottom with ledges *b*, on which are supported fixed transverse beams *c* and removable transverse beams *d*. In the bottom of the vat are arranged screen plates *e*, supported at their ends on the ledges *b* and are held in place by the beams *c* and *d*.

Along the side walls of the vat are provided clamps *f* comprising housings *g* arranged in recesses *h* in the side walls of the vat, spaced relatively with the ends of the removable cross beams *d*.

The housings *g* are provided with longitudinal slots *g'* on the sides facing the interior of the vat and with laterally projecting lugs *i* in which are threaded supplementary clamping screws *j*. Laterally extending ears *g''* are provided on the lower end of the said housing to hold them securely in their recesses. Within the housing is also threaded a clamping screw *k*, projecting upwardly through vertical holes *h'* bored in the said side walls. The screws *k* terminate in square shanks *k'* and are provided on their lower

ends with pressure blocks *l*, in which they are rotatably secured.

The blocks *l* are provided with lateral upwardly projecting lips *l'* and their lower surfaces are adapted to bear against the ends of the removable transverse beams *d*.

Arranged against the sides of the vat over the ends of the screen plates and the transverse beams, are lining-and-clamping bars *m*, rectangular in cross section and provided with packing *n* in their bearing faces. Recesses *o*, spaced correspondingly to the clamps *f* and adapted to receive the lips *l'* of the clamps are provided in the said lining bars and strike plates *p* are provided partially covering the said recesses, against which the lips *l'* bear upwardly.

By this arrangement and construction the transverse beams *c* and *d* and screen plates *e*, being in place and the pressure blocks *l* being tightly clamped down over the ends of the beams *d*, the lining-and-clamping bars *m* are then placed in position with the lips *l'* extending into the recesses *o*. The screws *j* are then screwed tightly down on to the upper edges of the lining bars, thus securely holding the screen plate in the bottom of the vat.

For conveniently operating the screws *j* and *k* a suitable socket wrench 2 may be used 30 as illustrated by Fig. 10.

When the screen vat is to be cleaned or the plates removed, the screws *j* will first be unscrewed taking the pressure off the lining bars, and then the screws *k* will be released, 35 which will release the pressure from the beams *d* and at the same time lift the lining bars clear of the accumulated pulp and waste, so that they may be conveniently removed, and the screen plates lifted therefrom by raising 40 one end sufficiently to clear the lugs *i*, and then withdrawing them longitudinally from the vat.

Thus by providing a pressure screw *k* for holding the screen plates in position in the 45 bottom of the vat, and a supplementary screw *j* for clamping the lining bars *m* in place, the latter may be removed without disturbing the screen plates, as when the vat is being cleaned by an attendant scraping or hosing the accumulated refuse therefrom.

I claim:

1. In a pulp strainer, in combination, a vat, screen plates, supporting means therefor and removable transverse beams locking the 55 screen plates in place, lining and clamping bars arranged along the interior faces of the vat walls and bearing on the screen plates, devices secured to the vat walls provided with means for clamping said beams and bars 60 in place, such devices comprising a casting having a screw threaded therein, and a block, slidably carried by said casting, removably secured to said screw and said casting provided with a projection having a clamping screw threaded therein bearing on said bars. 65

2. In a pulp strainer, in combination, a vat, screen plates, supporting means therefor and removable transverse beams locking the screen plates in place, lining and clamping bars arranged along the interior faces of the vat walls and bearing on the screen plates, devices secured to the vat walls provided with means for clamping said beams and bars in place, such devices comprising a casting having a screw threaded therein, and a block, 70 slidably carried by said casting, removably secured to said screw, said casting provided with a projection having a clamping screw threaded therein bearing on said bars and means inter-locking the said bars with said blocks. 75

3. In a pulp strainer, in combination, a vat whose interior faces are provided with vertical recesses, screen plates, supporting means therefor and removable transverse beams locking the screen plates in place, lining and clamping bars arranged along the interior faces of the vat walls and bearing on the screen plates, devices located in said recesses of the vat walls provided with means for 85 clamping said beams and bars in place, such devices comprising a casting having a screw threaded therein, and a block, slidably carried by said casting, removably secured to said screw and said casting provided with a 90 projection having a clamping screw threaded therein bearing on said bars.

4. In a pulp strainer, in combination, a vat, screen plates, supporting means therefor and removable transverse beams locking the 100 screen plates in place, lining and clamping bars arranged along the interior faces of the vat walls and bearing on the screen plates, devices secured to the vat walls provided with means for clamping said beams and bars in 105 place, comprising an elongated casting provided with a longitudinal channel in one end, a screw threaded in said casting projecting into said channel, and a block secured to said screw, slidably in said channel and said casting provided with a projection having a clamping screw threaded therein bearing on 110 said bars.

5. In a pulp strainer, in combination, a vat, whose interior faces are provided with vertical recesses, screen plates, supporting means therefor and removable transverse beams locking the screen plates in place, lining and clamping bars arranged along the interior faces of the vat walls and bearing on the 115 screen plates, devices located in said recesses of the vat walls provided with means for clamping said beams and bars in place, comprising an elongate casting provided with a longitudinal channel in one end, a screw threaded in said casting projecting into said channel, and a block secured to said screw, slidably in said channel and said casting provided with a projection having a clamping screw threaded therein bearing on 120 said bars. 125

screw threaded therein bearing on said bars. 130

6. In a pulp strainer, in combination, a vat, screen plates, supporting means therefor, and removable transverse beams locking the screen plates in place, lining and clamping bars arranged along the interior faces of the vat walls and bearing on the screen plates, devices secured to the vat walls provided with means for clamping said beams and bars in place, such devices comprising a casting having a screw threaded therein and a block, slidably carried by said casting, removably secured to said screw, said casting provided with a projection having a clamping screw threaded therein bearing on said bars and the block provided with a projection having a locking lip extending into a recess therefor provided in the clamping bar, the latter being provided with lugs engaging with the said locking lip.
- 10 7. In a pulp strainer, in combination, a vat whose interior faces are provided with vertical recesses, screen plates, supporting means therefor and removable transverse beams locking the screen plates in place, lining and clamping bars arranged along the interior faces of the vat walls and bearing on the screen plates and provided with packing on their bearing faces, devices located in said recesses of the vat walls provided with means for clamping said beams and bars in place, such devices comprising a casting having a screw threaded therein, and a block, slidably carried by said casting, removably secured to said screw, said casting provided with a
- 15 projection having a clamping screw threaded therein bearing on said bars and the block provided with a projection having a locking lip extending into a recess therefor provided in the clamping bar, the latter being provided with lugs engaging with the said locking lip.
